[57] CLAIM

The ornamental design for an animal-like figure toy, substantially as shown and described.

DESCRIPTION

FIG. 1 is an isometric view showing the front, one side and the top of an animal-like figure toy, showing my new design;

FIG. 2 is a side elevational view showing the other side of the animal-like figure toy of FIG. 1;

FIG. 3 is a rear elevational view of the animal-like

FIG. 4 is a bottom plan view of the animal-like figure toy of FIG. 1.
